UNITED STATES PATENT OFFICE

BENJAMIN C. VANDUZEN, OF WINTON PLACE, OHIO.

PUMP.

SPECIFICATION forming part of Letters Patent No. 375,027, dated December 20, 1887.

Application filed April 22, 1884. Serial No. 128,888. (No model.)

To all whom it may concern:

Be it known that I, BENJAMIN C. VANDUZEN, a resident of Winton Place, in the county of Hamilton and State of Ohio, have invented 5 certain new and useful Improvements in Pumps, of which the following is a specification.

My improvements are applicable to double-acting pumps, and also to single-acting ones.

10 The various features of my invention and the several advantages arising from their use, conjointly or otherwise, will be apparent from the following description and claims.

In the accompanying drawings, Figure 1 15 represents a vertical central section of a double-acting pump illustrating my invention, the pistons and drop or puppet valve, stay-rod of the forcing-cylinder, actuating-rod, upper end of pump-stock, and actuating-lever being shown. Fig. 2 represents a side elevation of 20 the upper portion of the pump shown in Fig. 1 and looking at that side of the pump which is on the left hand in Fig. 1. Fig. 3 represents a side elevation and also a top or plan 25 view of the preferred form of drop or puppet valve of the pump shown in the two preceding figures.

A indicates a pump-stock made of wood. The upper end of this stock carries the actuating-lever B, pivoted to said stock in any desirable manner. In this stock is a discharge-outlet, C, usually provided with a discharge-spout, C'. The discharge-outlet C connects with the discharge-conduit D, located within 35 the stock A, and the conduit D runs lengthwise with the stock. The lower end of the discharge-conduit connects transversely with the pump-cylinder E by means of a transverse or horizontal passage, D', passing through the 40 side of the stock and through the upper or discharge branch, E', of the cylinder into the piston-chamber E². This cylinder E is provided with a lower or inlet branch, E², through which is an inlet-passage, F, which latter also 45 extends through the side of the stock and communicates with the upper end or portion of the inlet-conduit F, located in the stock and running lengthwise therewith. In the stock and between the inlet-conduit F and discharge- 50 conduit D thereof is a partition, G, and the partition entirely separates the conduit F from

the conduit D and shuts off all communication between said inlet and discharge conduits.

The pump-stock is made of a single piece of wood. This wood is bored from one end lengthwise nearly to the other end. The tube thus bored is made use of for the inlet-conduit F and outlet-conduit D by introducing a plug, G, into the open end of this tube and driving this plug to a point in the tube between the orifice F' and orifice D'. This plug forms a partition between the inlet and discharge conduits and prevents their communication, except through the orifices F' and D'.

The suction-cylinder E preferably has a suction space or chamber, H, in its lower end, and above this is located a diaphragm, I, provided with a raised or sand seat, J, surrounded with sand groove or channel K. This valve-seat is preferably cast in one piece with the cylinder E. On this raised valve-seat rests a drop or puppet valve, L, preferably of the following construction; viz: A disk or plate, M, is provided with wings or radial arms m, whose exterior ends lie in a circle having a diameter nearly equal to the interior diameter of the cylinder E, so that the ends of the arms shall fit closely within said cylinder and yet allow the valve to slide up and down in the said cylinder. The arms m, or their under surface at least, are preferably inclined from the disk M upward as well as outward.

It is a desirable object to lift out the puppet-valve along with the pistons and the forcing-cylinder. Such an object may be attained 85 by means of a flexible connection, W, connected to the center portion of the bottom of the suction-piston, preferably by an eye, t, and to the center portion of the valve L, preferably by an eye, X. This flexible connection is sufficiently slack to allow the piston P to make its regular strokes without rendering the flexible connection taut.

The preferred description of flexible connection W is a chain, as shown.

When the pistons and forcing-cylinder Q are separated and withdrawn from cylinder E, the puppet-valve L is also withdrawn by means of said chain or connection W. When the said pistons, forcing-cylinder, and puppet-valve L are to be reinserted, the chain or connection suspends the said valve L, and by

holding this valve over the mouth of cylinder E the valve drops into said mouth, the inclined arms *m* aiding to guide the said valve into said mouth. After the said valve is within 5 said cylinder E the forcing-piston P and then the forcing-cylinder are inserted. During the operation of the pump the puppet-valve, although permanently connected to the piston P, is nevertheless, on account of the flexible 10 nature of that connection, free to rise from and fall back on its seat, according as the pressure of water is from above said valve or below it. The under side of plate M is preferably provided with a packing of leather, *n*, or other 15 suitable material.

The suction-piston P, working in suction-cylinder E, is constructed in any suitable manner, but so that it can be readily inserted in the cylinder E without disturbing the packing 20 which said valve carries. The forcing-piston Q is also constructed in any desirable manner.

The pistons P and Q are suitably connected to the actuating-rod S, the upper end of the latter being connected to the actuating-lever 25 B or equivalent motor. This suction-piston P and forcing-piston Q are rigidly connected together in any suitable manner. Piston Q works in the forcing-cylinder R. This forcing-cylinder R is connected to the suction-cylinder in any desirable manner, whereby 30 the forcing-cylinder may be easily dropped into or lifted out from its connection with the suction-cylinder.

A preferred mode and means of connection 35 consists as follows: The upper end or mouth, *e*, of the suction-cylinder is flared or inclined upward and outward. An annular flange or ring, *b*, having its peripheral surface inclined in a direction parallel to the inclination or 40 flare of the adjacent portion of the mouth *e* of suction-cylinder E, is rigidly connected to forcing-cylinder R. The middle diameter of this annular flange *b* is preferably about that of the interior diameter of the cylinder-mouth 45 *e* at the middle of the height of the said mouth *e*. The periphery of the annular flange *b* is provided with annular groove *b'*, extending in the flange *b* around the cylinder R, and this groove carries a packing, preferably round 50 in cross-section. Such a mode enables the forcing-cylinder to be readily inserted into or connected with the cylinder E, and also in a manner such as to make the joint between the two cylinders water-tight.

55 The preferred means for carrying the forcing-cylinder out of the suction-cylinder when the pistons L and R are raised, and also for pushing the forcing-cylinder into the suction-cylinder when the two cylinders are to be connected, and also for holding the forcing-cylinder to place in the suction-cylinder, are as follows: To the upper portion of forcing-cylinder R, preferably to an extension, *f*, of said cylinder, is connected a rod, T, by means of a 60 pivot rod or bolt, *g*. The connection between the forcing-cylinder R and the rod T is thus a 65 pivotal one. The forcing-cylinder is held to

place in or on the suction-cylinder through the agency of the rod T by any suitable means, the preferred means being as follows: The 70 upper end of the rod T is pivoted by a pivot, *h*, to the lower end of a lever, V. The latter is fulcrumed on a pivot-fulcrum, *p*, and has a suitable handle, as *l*. Pivot-fulcrum *p* is screwed into or otherwise secured to the 75 pump-stock. When the forcing-cylinder and pistons and puppet-valve L are to be withdrawn from the cylinder E, the handle, when located, as shown, being moved to one side and down, the lever V is turned, thereby starting the forcing-cylinder R from the mouth of cylinder E. Pivot *h* is now removed, and the upper end of the actuating-rod separated 80 from lever B, or lever B is separated from the pump-stock, and then rods S and T, forcing-cylinder, pistons, and puppet-valve are together drawn up and removed.

In replacing the parts, the puppet-valve, pistons P, and cylinder R are let down and reinserted in cylinder E, and the actuating-rod 90 again connected to lever B or the lever B to the pump-stock. The rod T is again connected to lever V by reinserting pivot *h*, and handle *l* is then raised, thereby, through the agency of the toggle-joint T *h* V, as the latter 95 is straightened, forcing the forcing-cylinder to place in cylinder E. When the toggle-joint is entirely straightened, it will, by means of the intervening rod T, hold the forcing-cylinder firmly down in place on or in cylinder E. 100 When desired, an air-vessel may be present. A preferred form of such air-vessel to be used in the discharge-conduit of the pump is as follows: D² indicates a tube closed at top and open at bottom. This tube is provided, 105 externally at or near each end with three or more spring or elastic parts or pieces, D³, preferably located at equal distances apart around the periphery of said tube. In the drawings four of such springs are disposed around each 110 end of the tube D². The preferable form of such springs is shown, viz: Each spring consists of a flat piece of metal, at its upper end rigidly united to the tube D². The lower portion of the spring is somewhat distant from 115 the periphery of the air-tube. The ends of the springs when not compressed lie in a circle whose diameter is greater than the diameter of the discharge-conduit. When the air tube or vessel D² is inserted in the conduit D, 120 the springs D³, being compressed, press against the interior surface of said conduit, and by the aid of friction hold the air-tube securely in place in the conduit.

The air-tube may be inserted into the discharge-conduit in any desirable manner. When the pump-stock is made of wood and bored, as described, the air-tube D² is first inserted through the inlet-conduit F, and thence into discharge-conduit D before plug 130 G is inserted. Then after the air-tube is in position the plug G is driven or passed into place. When desired, when the pump-stock is of wood, the free ends of the springs D³

may be made sharp to stick into the wood of the stock; but I prefer to make the ends somewhat curved or bent inward toward the tube, and thus present a rounded surface 5 against the inner surface of the stock and enable the tube to be, when necessity requires, more easily withdrawn from the stock, whether the latter be of wood or metal.

The operation of the aforescribed pump 10 does not differ essentially from that of other double-acting force-pumps. The elevation of piston P draws up the liquid through inlet-conduit F, orifice F', through valve seat J, and said liquid, lifting the puppet-valve L, enters 15 the cylinder E. As the piston P descends, the puppet-valve closes and the liquid passes through the piston P, past the valve in said piston, and enters the cylinder E above said piston P. As the pump continues to fill with 20 liquid, the descent of forcing-piston Q operates to force a certain quantity of liquid up through the discharge-conduit, while the elevation of piston P discharges another quantity of liquid through said conduit. The 25 liquid rising through the discharge-conduit is ejected from the spout or equivalent discharge-opening. Thus the liquid issues from the pump in a continual stream, this stream being kept still more even by reason of the presence 30 and action of the air-vessel D². The cylinder E is suitably connected to the pump-stock. In the present instance flanges at the sides of the inlet branch and at the sides of the outlet branch of said cylinder are provided, and 35 through each flange and through the pump-stock is passed a bolt, y, four bolts thus holding the cylinder E to the pump-stock. The

pump-stock and the air-vessel and the puppet-valve and its seat and the flexible connection W, or any one or more of these, may be employed in a single-acting pump or in a double-acting pump having a forcing-cylinder of different description from that herein shown.

I would here mention that while the various features of my invention are preferably employed together, one or more of them may be employed without the remainder, and one or more of said features may, so far as applicable, be employed in connection with pumps or pumping devices other than those herein particularly specified.

What I claim as new and of my invention, and desire to secure by Letters Patent, is—

1. In a pump, the combination of a suction-cylinder and a removable forcing-cylinder 55 and rod T, pivoted to the forcing-cylinder, and toggle-joint T h V, substantially as and for the purposes specified.

2. In a pump, the combination of a suction-cylinder and a removable forcing-cylinder 60 provided with extension f, pivot g, rod T, pivot h, lever V, and pivot p, substantially as and for the purposes specified.

3. In a pump, the combination of the suction-cylinder, puppet-valve, suction-piston, 65 flexible connection between said piston and valve, removable forcing-cylinder, forcing-piston, rod T, pivoted to the forcing-cylinder, and toggle-joint, substantially as and for the purposes specified.

BENJAMIN C. VANDUZEN.
